Patented Dec. 4, 1917.

UNITED STATES PATENT OFFICE.

ROBERT N. EGGLESTON, OF ST. LOUIS, MISSOURI, ASSIGNOR TO MULTIPULL MANUFACTURING COMPANY, OF ST. LOUIS, MISSOURI, A CORPORATION OF MISSOURI.

PULLING DEVICE.

1,248,470.

Specification of Letters Patent.

Patented Dec. 4, 1917.

Application filed April 3, 1917. Serial No. 159,436.

To all whom it may concern:

Be it known that I, ROBERT N. EGGLESTON, a citizen of the United States, residing at St. Louis, Missouri, have invented a certain new and useful Improvement in Pulling Devices, of which the following is a full, clear, and exact description, such as will enable others skilled in the art to which it appertains to make and use the same.

10 This invention relates to devices of the character that are used for exerting a pull on a rope, chain, cable or other flexible member connected to an object which it is desired to move.

15 The main object of the invention is to provide an inexpensive pulling device of the character referred to that is compact, easy to operate and easy to install or set up.

Another object is to provide a pulling device of the character referred to which is so constructed that a number of persons can be used to operate it.

20 And still another object is to provide a pulling device which is constructed principally from material that can usually be bought in the open market in any desired quantities, such, for example, as metal pipe, pipe fittings and bar iron.

25 Briefly described, my improved pulling device consists of a vertically-disposed winding shaft, a rope, chain, cable or other flexible member that leads from the object to be moved to the winding shaft, a collapsible frame provided with bearings in which 30 said shaft turns, means for anchoring said frame to the ground and a device for turning the winding shaft so as to wind the flexible pulling member onto same.

35 Figure 1 of the drawings is a perspective view, illustrating a pulling device constructed in accordance with my invention used for extracting an automobile from the mud.

40 Fig. 2 is a front elevational view of said device.

45 Fig. 3 is a side elevational view of said device.

Fig. 4 is a front elevational view, showing the supporting frame for the winding shaft collapsed.

50 Fig. 5 is an enlarged horizontal sectional view, taken on the line 5—5 of Fig. 3.

Fig. 6 is a detail view, illustrating a piece of rope provided with a device of slightly different form from that shown in Fig. 2

for connecting the rope to the winding shaft; and

Fig. 7 is a perspective view of a spade or shovel that can be used in sandy soil in place of the ground anchors shown in Fig. 1 for anchoring the pulling device to the ground.

Referring to the drawings which illustrate the preferred form of my invention, A designates the winding shaft of the device which is rotatably mounted in two bearings 1 and 2 of a collapsible frame that is constructed in such a manner that it can be folded up compactly, as shown in Fig. 4, when the device is not in use and opened or unfolded, as shown in Fig. 2, when the device is in use.

65 The device comprises a flexible pulling member B, such, for example, as a rope, chain or cable that leads from the object to be moved, herein shown as an automobile x, to the winding shaft A, and means is provided for anchoring the winding shaft frame to the ground, so as to prevent it from moving when the shaft A is being turned to wind the flexible member B onto same.

70 Any suitable means may be used for anchoring the winding shaft frame to the ground, but I prefer to use a flexible anchoring member C which may consist of a chain, rope or cable secured to the lower end portion of the winding shaft frame and one or more ground stakes D for anchoring the member C to the ground.

75 A flexible brace C', which may consist of a piece of chain, rope or cable, is connected to the upper end portion of the winding shaft frame and to the flexible anchoring member C, preferably at a point slightly in advance of the first

80 ground stake, as shown in Fig. 1, so as to assist in holding the winding shaft frame in an upright position when the device is in use.

85 The winding shaft frame can be formed in various ways without departing from the spirit of my invention, but I prefer to form said frame from a top member 3 and a bottom member 4 that are joined together by two pairs of links 5 and 6 which are so proportioned and arranged that when

90 the winding shaft frame is open, as shown in Fig. 2, the links 5 will project laterally from the bottom member 4 of the frame, and thus form a relatively wide base portion, and the links 6 will be inclined upwardly and

95 inwardly from the ends of said base portion.

100

105

to the top member 3 of the frame. The top and bottom members 3 and 4 of the winding shaft frame preferably consist of castings that have integral hooks 7 to which the flexible anchoring member C and brace C' are connected, the top and bottom bearings 1 and 2 for the winding shaft being formed integral with said castings, and said castings also having integral, bifurcated ears 8 to which the links 5 and 6 are pivotally connected by pivots 9. The bottom member 4 of the winding shaft frame is mounted on said winding shaft in such a manner that it can be moved upwardly longitudinally of same, thus permitting the links 5 and 6 to be folded or arranged in a position substantially parallel to the winding shaft when the device is not in use. When the winding shaft frame is unfolded or in its open position, as shown in Fig. 2, a flanged or flared portion 10 at the lower end of the winding shaft, shown more clearly in Fig. 4, bears against the bottom bearing 2 on the winding shaft frame in such a manner that said shaft 25 cannot move upwardly.

The winding shaft A is provided at its upper end with a head portion 11 in which a device 12 can be inserted so as to form a lever or handle for turning the winding shaft. The head portion 11 is preferably formed from a T-shaped pipe fitting screwed onto the upper end portion of the winding shaft and having two internally threaded openings into which handles or levers 12 and 12^a can be inserted, as shown in Fig. 2, in case it is desired to employ more than one person to operate the device.

In using the device the end of the flexible pulling member B is preferably secured to the winding shaft A in such a manner that said pulling member will not slip when the winding shaft is turned. One convenient way of securely connecting the pulling member to the winding shaft is to provide said 45 pulling member with a pin 13, as shown in Fig. 2, that can be inserted in a hole 14 in the winding shaft, said pin either being arranged transversely in the flexible pulling member A, as shown in Fig. 6, or having 50 a portion or portions 13^a that surround said pulling member, as shown in Fig. 2. After the pulling member B has been connected to the winding shaft, said shaft is turned so as to cause the pulling member B to be wound 55 onto same, and after the object being moved has moved the desired distance, the winding shaft A is locked against movement in the reverse direction by means of a hook-shaped locking device 15 that is arranged 60 in engagement with the handle 12 and with the pulling member B, as shown in Fig. 1. The flexible anchoring member C and brace C' prevent the winding shaft frame from tilting forwardly or toward the object being 65 moved when the winding shaft is being op-

erated to wind the pulling member B onto same, and the relatively wide base portion of said frame, which rests upon the ground, prevents the frame from tilting sidewise in either direction. The top side of the bottom 70 member 4 of the winding shaft frame and the bottom side of the top member 3 of said frame are preferably made slightly convex, as shown in Fig. 2, so as to cause the flexible pulling member B to wind evenly onto the 75 shaft A.

My improved device can be used in various ways and for various purposes, but it is intended to be used principally by automobileists for extracting an automobile that 80 is mired in the mud or in sandy soil. Therefore, in selling the device I furnish with same a spade or shovel D' of the kind shown in Fig. 7 that can be used in sandy soil in place of the stakes D to anchor the flexible 85 member C to the ground. The handle of said spade is formed from two pieces of pipe or tubing 12 and 12^a that are connected together by a coupling 12^b, and the blade of said spade is provided with a hook or ring 90 12^c to which the flexible anchoring member C can be connected. By constructing the spade in this manner the handle of same can be used as a lever to turn the winding shaft A, thus reducing the cost of the complete 95 apparatus and permitting it to be stored away in a small space. When the spade D' is used to anchor the member C, the handle is connected to the blade of the spade and the spade is then used to dig a hole in the 100 ground. The handle is then disconnected from the blade, the blade then arranged in the bottom of the hole, and after the flexible member C has been connected to the ring or hook 12^c on the blade, the hole is filled 105 up by scraping the dirt back into same. The winding shaft frame is then unfolded and arranged in an upright position, and after the flexible members C and C' have been connected to the frame and the pulling member 110 B has been connected to the winding shaft, the handle of the spade is screwed into the head portion 11 at the upper end of the winding shaft so as to form a handle or lever by which said winding shaft can be 115 turned in the manner previously described. While I prefer to connect one end of the pulling member B to the winding shaft by means of a pin on the pulling member that is inserted in a hole in the winding shaft, it 120 is not essential that the pulling member be pinned or connected to the winding shaft in this manner, for if desired, the pulling member can be looped around the winding shaft in such a way that the end of same is left 125 free. Whenever a long rope or cable is used as the pulling member it is wrapped around the winding shaft in this manner, the free end portion of the rope being taken up as the portion of the rope between the wind- 130

ing shaft and the object being moved is wound onto the shaft.

A winding device of the character above described can be manufactured at a low cost 5 on account of its simple construction, as it consists merely of a collapsible frame, a shaft journaled in bearings in said frame and flexible members for anchoring the frame to the ground and for connecting 10 the winding shaft with the object to be moved. When the device is not in use it can be stored in a small space, and when it is in use the winding shaft frame of same is prevented from tilting either forwardly 15 or sidewise by the inclined brace C' and by the relatively wide base portion of the frame. Most of the parts of the device, such, for example, as the winding shaft, the head portion of same, the handle or lever 20 by which the winding shaft is turned and the links 5 and 6 of the winding shaft frame are formed from material that can be purchased in large quantities in the open market at any time, the only parts of the de- 25 vice that require special material being the top and bottom members of the winding shaft frame, each of which consists of a casting of simple design. Consequently, the device can be manufactured cheaply and suitable 30 material is always available for the manufacture of the device.

Having thus described my invention, what I claim, and desire to secure by Letters Patent, is:

35 1. A pulling device, comprising a winding shaft that is adapted to be turned so as to wind a flexible pulling member onto same, a frame comprising a top bearing and a bottom bearing in which said shaft is jour- 40 naled, and a collapsible means for connecting said bearings together, said means being so constructed that the bottom bearing will move longitudinally of said shaft when said means is collapsed.

45 2. A pulling device, comprising a winding shaft onto which a flexible pulling member is adapted to be wound, a supporting frame for said shaft comprising a top member and a bottom member, and links pivotally connected to said members in such a manner that they can be arranged in such a position that some of said links form a relatively wide base supporting portion and the remaining links form inclined elements that 50 connect said base supporting portion to said top member.

3. A pulling device, comprising a winding shaft onto which a flexible pulling member is adapted to be wound, a supporting frame for said shaft formed by a top and a bottom member in which said shaft is journaled, and a plurality of links pivotally connected to each of said members in such a manner that they can be collapsed so as to arrange said links in substantially parallel 60 relation to said shaft and also force said bottom member upwardly toward said top member.

4. A pulling device, comprising a winding shaft onto which a flexible pulling member 70 is adapted to be wound, a supporting frame for said shaft provided with top and bottom members provided with bearings in which said shaft is journaled, a base portion pivotally connected to said bottom 75 member, and inclined elements pivotally connected to said base portion and to said top member.

5. A pulling device, comprising a winding shaft onto which a flexible pulling member 80 is adapted to be wound, a supporting frame provided with bearings for said shaft, one of which can move longitudinally of said shaft, a collapsible connecting means for said bearings, and a head portion on said 85 winding shaft to which a lever or handle can be detachably connected.

6. A pulling device, comprising a winding shaft onto which a pulling member is adapted to be wound, a frame comprising a 90 top member and a bottom member provided with bearings in which said shaft turns, devices on the rear sides of said members to which a combined anchoring and bracing means can be connected, and pairs 95 of links pivotally connected together and also joined to said top and bottom members in such a manner that they can be arranged in a position substantially parallel to said winding shaft when the device is not in 100 use.

7. A pulling device, comprising a winding shaft onto which a flexible pulling member is adapted to be wound, a collapsible frame comprising top and bottom members provided with integral bearings in which said shaft turns, integral lugs on said bearings that project laterally from same, and two pairs of links pivotally connected together and also pivotally connected at their free 110 ends to said lugs.

ROBERT N. EGGLESTON.
